Attorney

UNITED STATES PATENT OFFICE.

WILLIAM H. MIDDLETON, OF NIAGARA FALLS, ONTARIO, CANADA, ASSIGNOR TO
AMERICAN CYANAMID COMPANY, OF NEW YORK, N. Y., A CORPORATION OF
MAINE.

PROCESS OF MANUFACTURING CYANAMID.

1,315,678.

Specification of Letters Patent.

Patented Sept. 9, 1919.

Application filed May 14, 1919. Serial No. 297,071.

To all whom it may concern:

Be it known that I, WILLIAM H. MIDDLETON, a citizen of Canada, residing at Niagara Falls, in the Province of Ontario and Dominion of Canada, have invented certain new and useful Improvements in Processes of Manufacturing Cyanamid; and I do hereby declare the following to be a full, clear, and exact description of the invention, such as will enable others skilled in the art to which it appertains to make and use the same.

This invention relates to a process of producing calcium cyanamid and has for one of its objects to improve certain of the prior processes which have been heretofore proposed.

With this and other objects in view the invention consists in the novel steps and combinations of steps constituting the process, all as will be more fully hereinafter disclosed and particularly pointed out in the claims.

Referring to the accompanying drawings, forming a part of this specification in which like numerals designate like parts in all the views:—

Figure 1 is a central vertical sectional view of an apparatus suitable for carrying out the present process; and

Fig. 2 is a fragmentary cross sectional view, taken on the line 2—2 of Fig. 1.

In order that the precise nature of the invention may be the more clearly understood it is said:—

In the manufacture of cyanamid under certain of the prior processes, it has been the practice to fill a metal container with finely ground calcium carbide and to then place the said container together with its charge of carbide in an oven lined with suitable refractory and heat insulating material. A suitable electrical resistor is inserted axially through the container in a suitable space provided therefor, the lid is placed on the oven, nitrogen is admitted and the current turned on to the resistor. At a temperature upward of 800-1000° C. the hot carbide adjacent to the resistor takes up nitrogen and is converted into cyanamid. This reaction progresses throughout the

mass until the whole is more or less completely converted into cyanamid when the mass is left to cool and the container with its content of cyanamid is removed and the oven made ready for a new charge.

The great wear and tear on the said metal containers when subjected to the high temperatures above indicated has proven a source of serious trouble and expense, the said containers becoming dented and battered through handling, making it difficult if not impossible to discharge the solid cake of cyanamid therefrom.

To obviate this difficulty and particularly during the war, when the cost of the metal containers became excessive, a substitute for the same was sought and found, consisting in a paper sleeve which was inserted into the oven and then filled with carbide, after which nitrification was started in the usual manner. This paper sleeve must be manufactured from stout paper and of definite dimensions and even with the greatest care, it would not infrequently tear or split from the pressure of the contained powdered carbide. Further, it was necessary that an annular space be left between the paper and the oven for inserting the proper equipment for placing the paper and holding it in place during filling with carbide, as well as to assist in distribution of nitrogen, and this said space appreciably reduced the capacity of a given sized oven and also increased the cost of equipment and housing.

In the present invention, I contemplate eliminating the metal container or the paper container entirely and in place of using these containers I propose to take the ordinary cyanamid oven, cylindrical in form and provided with the usual refractory lining, and line the same with a single sheet of corrugated paper, or preferably corrugated strawboard and to then insert the usual paper cylinder for forming a space for the resistor after which I can fill up the whole oven with carbide.

The strawboard may be used in sheets without special forming, as they are merely laid around the inside wall of the oven with suitable lap. That is to say, prior to this invention, owing to the tendency of the very

finely ground carbid to pack into more or less dense masses, it has been thought by those skilled in this art that it was essential that a considerable space be left all around 5 the carbid in order to provide a sufficiently spacious passage for the nitrogen. One instance of such a space is shown in Patent #1282381, Oct. 22, 1918, to G. E. Cox.

I have discovered on the other hand, that 10 it is not necessary to provide any such ample space for the nitrogen as that heretofore employed, and that in fact if one takes ordinary corrugated paper, or other similarly corrugated material such as is used for 15 packing purposes in commerce, and lays it flat against the inside walls of the oven, as indicated, a sufficient space will be provided for the passage of the nitrogen while the total output of the oven will be greatly increased 20 owing to the greater quantity of carbid one can charge therewith. In this manner of operating, a given oven will in fact hold say 35 per cent. more carbid than where the prior paper sleeve was used and 25 nearly 50 per cent. more than where the prior metal container was used and without any change whatever in the structure of the oven itself. The nitrogen is commonly led in through the side and at the bottom of the 30 oven, and I cover this inlet with broken strips of corrugated strawboard extending them to the center tube and also to the top of the corrugated lining and in this way distribute nitrogen through the broken up strawboard both to the center and to the top 35 of the oven.

Referring now to the accompanying drawing, 1 represents the metal shell of the usual cyanamid oven, lined with the refractory 40 and heat insulating material 2 around the periphery and the bottom thereof, for the purpose of protecting the said metal shell, and also for conserving the heat in the oven. 3 represents a metal cover, also lined with 45 heat insulating material 4 and resting in a sand seal 5. 6 indicates an annular ring of corrugated paper resting on the bottom of the oven as shown and 7 a nitrogen inlet pipe ending at the inside of the refractory 50 lining 2.

In order to provide for the distribution of the nitrogen as it comes from the said tube 7, I crinkle up a small piece of corrugated paper 8 of sufficient length to reach to the 55 center of the oven and lay it from the nitrogen feed line 7 to the center of the oven as shown, and I further fold up a narrow strip of this corrugated board and hold it vertical from above the nitrogen intake as shown at 60 9. I next line the whole inside of the walls of the oven with a sheet of corrugated paper 10 so as to include the folded piece 9 between it and the said walls, and I then insert 65 a paper tube 11 in the center of the oven and fill the oven with finely ground calcium car-

bid 12. After inserting the resistor 13 within the tube 11, I place the cover 3 on the oven, turn on the nitrogen and then the current, and start nitrification. The nitrogen itself is fed to the center around the resistor 70 and up the sides of the oven as well as into the mass of carbid itself, through the use of the crinkled corrugated paper. Nitrification proceeds in the usual manner.

During the nitrification the straw board 75 around the walls chars, owing to the intense heat, and the ingot of cyanamid shrinks away from the walls sufficiently so that if proper taper is given to the oven lining, it is a comparatively simple matter to withdraw 80 the ingot. For holding the ingot during withdrawal I sink into the mass of fine carbid before starting nitrification, one or more iron rods 15 bent over at the bottom and ending in a ring above the top of the carbid 85 so that a crane or other hoisting device may pick up the ingot of cyanamid by attaching hooks to these said rings.

The strawboard lining used in the present process, is much cheaper than even a paper sleeve such as has been used heretofore, due to the fact that it may be made of relatively cheaper material and also to the fact that it does not need to be specially formed to any particular size. Further the close contact 95 of the carbid with the oven walls gives a better reflection of heat to the mass, resulting in more perfect nitrogen fixation at that point. As a result, with identically the same carbid, I obtain a better absorption of 100 nitrogen, a smaller amount of unnitritified carbid, and a better carbid efficiency for the full oven than for the same oven with the paper sleeve. The amount of current necessary for starting the oven is not greater than 105 where the paper sleeve is used and due to its larger capacity, it actually amounts to less kilowatt hours per ton of product than where the paper sleeve is used.

I have further found that I obtained a 110 slightly greater efficiency in utilization of the nitrogen, probably because the mass of carbid under treatment in the oven is greater at one time.

Where oven linings have a slight taper 115 and are fairly smooth inside, I have even succeeded in eliminating the use of the corrugated strawboard 10, around the lining 2 and still have been able to remove the ingot of cyanamid without it adhering to the 120 walls. In this case it is however necessary to distribute the nitrogen by means of the broken up strawboard just as if the oven itself were lined as described above, and where the linings 2 are more or less rough 125 it is preferable to use the corrugated strawboard lining 10 as above disclosed.

It is obvious that those skilled in the art may vary the details of the apparatus for carrying out the invention, as well as the 130

steps constituting the process, without departing from the spirit of the invention, and therefore I do not wish to be limited to the above disclosure except as may be required 5 by the claims.

What I claim is:—

1. The process of producing cyanamid which consists in charging carbid directly into a suitable oven; providing a free space 10 in said charge to accommodate a resistance element, placing against the inside of said oven a material having an uneven surface to provide a multitude of additional free spaces for the nitrogen in close proximity 15 to the inside of said oven to facilitate the distribution of nitrogen through said charge; introducing nitrogen into said spaces; and passing a current through said element whereby the temperature in said 20 oven is raised to a point sufficient to cause said nitrogen to react with said carbid, substantially as described.

2. The process of producing cyanamid which consists in lining the refractory walls 25 of an oven with a combustible material having an uneven surface; providing a sleeve of combustible material adapted to surround a heating element in said oven; charging the said oven with finely divided carbid; providing a conduit of combustible material in 30 said charge adapted to facilitate the distribution of nitrogen therein; introducing nitrogen into said conduit; and raising the temperature in said oven to a point sufficient to consume said combustible material 35

and to cause said nitrogen to react with said carbid, substantially as described.

3. The process of producing calcium cyanamid which consists in lining the refractory walls of an oven with corrugated straw-board material; inserting a tube of straw-board material in said oven to provide an open space for a heating element; providing conduits of strawboard material in said oven to facilitate the distribution of nitrogen 40 therein; charging the said oven with a calcium carbid; introducing nitrogen into said oven; and suitably raising the temperature in said oven to a point where said straw-board material is charred and said nitrogen 45 will react with said carbid to form cyanamid, substantially as described.

4. The process of increasing the output of cyanamid ovens which consists in lining said ovens with corrugated sheet material 50 pervious to nitrogen gas but impervious to finely ground carbid to provide a multitudinous number of small passages for said gas; providing a passage for said gas in the body of said carbid; filling said oven to its lined 55 walls with a charge of carbid; introducing nitrogen into the charge and igniting the latter, substantially as described.

In testimony whereof I affix my signature in presence of two witnesses.

WILLIAM H. MIDDLETON.
